PAGE 5

Fig. 7.

FIGURE 1 is a front top perspective view of a combination windrower and swather, showing our new design; FIG. 2 is a front perspective view thereof;

FIG. 3 is a perspective view, showing one side thereof; FIG. 4 is a perspective view, showing the other side thereof;

FIG. 5 is a rear perspective view thereof;

FIG. 6 is a top perspective view thereof;

FIG. 7 is a front top perspective view, showing a modified form of our combination windrower and swather;

FIG. 8 is a rear top perspective view of the form shown in FIG. 7;

FIG. 9 is a perspective view of one side of the form shown in FIG. 7; and

FIG. 10 is a side elevation of the form shown in FIG. 7.

The dominant features of our design reside in the portions shown in full lines.

We claim:

The ornamental design for a combination windrower and swather, substantially as shown and described.
